UNITED STATES PATENT OFFICE.

CHARLES W. BROWN, OF UTICA, NEW YORK, ASSIGNOR TO THE SINGER MANUFACTURING COMPANY, A CORPORATION OF NEW JERSEY.

FOLDING AND TRIMMING MECHANISM FOR SEWING MACHINES.

Application filed July 20, 1918. Serial No. 245,848.

To all whom it may concern:

Be it known that I, CHARLES W. BROWN, a citizen of the United States, residing at Utica, in the county of Oneida and State of New York, have invented certain new and useful Improvements in Folding and Trimming Mechanisms for Sewing Machines, of which the following is a specification, reference being had therein to the accompanying drawings.

This invention relates to an improvement in the constructions employed for attaching edging strips to garments and particularly edging strips of knit or other elastic material.

In machines heretofore employed for attaching edging strips to garments, and thereby finishing the edges thereof it has been a common practice to attach the strip to the body-fabric in the form of a binding embracing the edge of the body-fabric. In order to obviate waste in material, the edges of the binding strip were caused to overlap the edge of the body-fabric as little as possible, but in doing so the rapidity of manufacture particularly of knit goods garments was greatly reduced.

The primary object of this invention is to attach an edging strip to a garment at a higher rate of speed than heretofore possible and in a manner occasioning less waste in material, at the same time securely enclosing the free edges of the garment and the edging strip.

More specifically, the invention has for its object to provide a trimming and over-edging machine with a folder adapted to guide an edging strip and uncurl the edges thereof so that its edges lie in substantial alignment and in superposed relation with an edge of the body-fabric, thereby permitting the trimming of the body-fabric and the edging strip simultaneously and the uniting of the same by overedge stitches.

In the preferred embodiment of the invention, there is employed a trimming and over-edging machine substantially as disclosed in the United States patent to A. Grieb, No. 932,272, dated August 24, 1909.

Adjustably secured upon the machine frame and extending in the direction of feed is a folder for an edging strip adapted to fold the latter into a horizontal U-shape. The receiving end of the folder is inclined to the direction of feed and is adapted to invert

the edging strip and guide it in a manner such that it is fed substantially at right angles to its initial direction of feed. As the edging strip passes over the inclined receiving end of the folder, the edges of said strip are uncurled with the aid of a tensioning device for the strip positioned intermediate the strip-supply and the folder. A guide is provided to direct the body-fabric to the trimming mechanism so that the edge of said body-fabric is in substantial alignment with the free edges of the edging strip, thereby permitting the simultaneous trimming by the machine of the raw edges of both, after which the fabric is fed to the overedging mechanism of the machine. After completion of the seaming operation, the fabrics are opened out and ironed flat.

In the accompanying drawings, Fig. 1 is a front side elevation of a sewing machine embodying the present improvement. Fig. 2 is a plan view of the sewing machine, omitting the overhanging arm. Fig. 3 is a perspective view of a portion of the trimming mechanism and of the edge-guide. Fig. 4 is a perspective view of the folder and its supporting arm. Fig. 5 is a sectional view of the trimmed and overedged body-fabric and edging strip. Fig. 6 is a sectional view similar to Fig. 5 but with the fabrics opened out preparatory to ironing the seam.

Referring to the drawings, the sewing machine is supported on a base 1 and includes the usual cloth-plate 2 and overhanging arm 3 terminating in the inclined head 4. As the sewing machine shown in the accompanying drawings is substantially the same as that clearly shown and described in the United States Patent No. 932,272 hereinbefore referred to, detailed description of the several actuated mechanisms is deemed unnecessary and is therefore omitted. Mounted for reciprocation in the head 4 is the needle-bar 5 carrying the needle 6. Cooperating with the needle in the formation of over-edge stitches is the needle-thread engaging looper 7 and the looper-thread engaging looper 8 operated in the usual manner. The trimming mechanism includes a stationary blade 9 and a cooperating movable blade or severing element 10, the latter of which is carried by the front end of a vibrating arm 11 supported and actuated in the usual manner.

Adjustably secured to the base 1, by screws as 12, is the supporting arm 13 of an edging strip folder. The folder consists of substantially U-shaped strip-folding walls 5 14 and 15 of which the extremities are doubled back upon themselves, thereby forming enclosing walls 16 and 17 spaced from the walls 14 and 15. The curved uniting portions 18 and 19 between the walls 14 and 16 10 and the walls 15 and 17 form edge-guides for the edging strip. The receiving end of the folder is inclined to its longitudinal axis, forming strip inverting edges, as 20, which in conjunction with the fold forming 15 edge 21 act to fold the latter into substantially horizontal U-shape and uncurl the edges of the strip. The edging strip *s* is led to the folder from a suitable strip-supply 20 in a direction substantially at right angles to the direction of its delivery by the folder to the trimming mechanism. Intermediate the folder and the strip supply is a tensioning device comprising a plurality of tension-pins 23, carried by a supporting 25 arm 24, projecting from the strip-supply holder 25.

A suitably secured edge-guide 26, located intermediate the strip-folder and the trimmer, is adapted to guide the edge of a body-fabric *b* in superposed relation with respect to the edging strip and in alinement with the edges of the latter to permit the severing element 10 to simultaneously trim the superposed edges, after which they are united by 30 the overedge stitches, as *t*. The body-fabric may be led directly over the folder, or through either of the strip-guiding passages thereof. By this means, the body-fabric may be united with either the upper or under side of the folded strips as may be desired. The combination described permits 35 of the attachment of edging strips to body-garments at a considerably greater speed than heretofore and with a very small waste 40 of material, thereby greatly lessening the cost of manufacture of the garments.

Having thus set forth the nature of the invention, what I claim herein is—

1. In a sewing machine, the combination 50 with over-edge stitch-forming mechanism including a needle, and an over-the-edge operating thread-carrying implement complementary to the needle in the formation of fabric-margin embracing stitches, of a strip-folder having spaced folding edges inclined 55 with respect to the line of feed, and means

for supporting said strip-folder whereby a strip of fabric is introduced between said inclined edges and is thence led thereover into the line of feed. 60

2. In a sewing machine, in combination, an edge-guide for a body-fabric, a strip-folder having a fold-producing portion disposed with respect to said edge-guide to present both plies of a folded strip on one side 65 of the body-fabric, trimming mechanism including a trimmer blade disposed with respect to said edge-guide and said strip-folder to sever the free edges of the folded strip and the guided edge of the body-fabric, and overedge stitch-forming mechanism including an over-the-edge operating implement to embrace by overedge stitches the margins of the fabrics. 70

3. In a sewing machine, in combination, 75 overedge stitch-forming mechanism including a needle and an over-the-edge operating thread carrying implement complementary to the needle in the formation of fabric-margin embracing stitches, fabric trimming mechanism including a blade operating entirely 80 across the work position, and a strip-folder disposed in advance of the effective portion of said trimming mechanism. 85

4. In a sewing machine, the combination 90 with stitch-forming mechanism including a reciprocating needle, and trimming mechanism including cooperating cutting elements located at one side and in advance of the point of penetration of the work by the needle, of a body-fabric edge-guide disposed on the same side of said needle as said cutting elements, and a strip-folder having a fold-producing portion disposed on the side of the needle opposed to said cutting elements 95 and edge-guide. 100

5. In a sewing machine, the combination with overedge stitch-forming mechanism including a needle, and an over-the-edge operating thread-carrying implement complementary to the needle in the formation of fabric-margin embracing stitches, of a strip-folder formed with a portion inclined with respect to the line of feed and merging into a fold-defining edge, and means for supporting said strip-folder in advance of the stitch-forming mechanism with the fold-defining edge in a line substantially parallel with the line of seam-formation. 105

In testimony whereof, I have signed my name to this specification.

CHARLES W. BROWN.
